UNITED STATES PATENT OFFICE.

JOSEPH C. ANDERECK, OF ALGOMA, WISCONSIN.

SPRING COVER.

Application filed June 9, 1925. Serial No. 36,028.

To all whom it may concern:

Be it known that I, JOSEPH C. ANDERECK, a citizen of the United States, residing at Algoma, in the county of Kewaunee and State of Wisconsin, have invented certain new and useful Improvements in Spring Covers, of which the following is a specification, reference being had to the accompanying drawings.

10 This invention relates to spring covers and more particularly to a cover for the leaf springs of automobiles intended to protect them from collection of dust and to maintain in contact with the spring a suitable lubricant therefor.

An important object of the invention is to provide a device of this character which may be readily applied to the vehicle spring and which, when applied, may be readily 20 opened to permit oiling of the spring.

A further object of the invention is to provide a structure of this character permitting the use of clips for the spring and at the same time providing a closely fitting 25 cover which will not interfere with the operation of the spring.

These and other objects I attain by the construction shown in the accompanying drawings, wherein for the purpose of illustration is shown a preferred embodiment of 30 my invention and wherein:

Figure 1 is a side elevation partially broken away showing a spring cover constructed in accordance with my invention applied to a vehicle spring;

Figure 2 is a sectional view therethrough;

Figure 3 is a section on the line 3—3 of Figure 1;

Figure 4 is a detailed longitudinal sectional view taken through one end of the cover;

Figure 5 is a modified form of the device and a modified manner of clipping the spring;

Figure 6 is a fragmentary plan view of the material employed in the construction of the form of invention illustrated in Figure 5;

Figure 7 is a combined perspective of 10 portions of the clip strips; and

Figure 8 is a perspective of the clamp employed for sealing the end of the cover to the spring.

Referring now more particularly to the 15 drawings, the cover comprises a length of fabric 10 to extend between adjacent points

of attachment of the leaf spring. For a quarter elliptic spring, it will be made of a length extending between the mounting of the butt of the spring and the shackle 60 end thereof while for a semi-elliptic spring, it will be made of a length extending between the central fastening of the spring and the shackle connection of the end thereof. On the last named type of spring there 65 will be, of course, two covers provided. This length of material is tapered from end to end so that it accommodates changes of size of the spring from end to end and each edge thereof has attached thereto a 70 clip strip 11 or 12. Each clip strip 11 has one end thereof reverted, as at 13 and clamped upon one longitudinal edge 14 of the material and its opposite edge oppositely reverted in spaced relation to the strip, as 75 at 15. In the bight between the reverted portion 15 and the strip 11, a cord 16 is disposed. Each strip 12 has one edge thereof reverted, as at 17, and clamped upon the second longitudinal edge 18 of the material. The opposite edge of the strip 12 is reverted upon the same side of the strip, as at 19, and has disposed in the bight between this reverted portion and the strip 20. I will be obvious that the strip 80 of material 10 may be placed about the spring and the reverted portions 15 and 19 of the clip strips 11 and 12 hooked to one another. Once hooked in position, it will be held in assembled relation by employing 85 a hammer or the like to clinch these reverted portions upon one another.

Before applying the strip to the spring, a strip of cotton roving 21 is wound about the spring for substantially the full length 90 of the spring which is to be covered. At each end of the strip 10 of the material upon the inner face thereof a transversely extending felt strip 22 is secured to the material and about each end of the cover, as applied, 95 a clamp 23 is disposed very firmly forcing the felt strip into engagement with both the cover and the spring so as to afford a seal at the ends of the cover against the 100 passage of oil.

A proper clipping of the leaf spring to prevent spreading thereof may be taken care of in either one of two manners. In Figure 1, the cover is shown as provided at intervals along its length with spring metal 110 clips 24 having their edges included in the connection between the edges of the strip

of material and the clipping strips 11 and 12. In Figure 5, the spring clip already applied to the automobile is shown as having its bolt removed and its end portions bent 5 to engage the spring. The strip of material forming the cover in this form of the device is so formed as to provide a pocket where the clips of the spring occur. This pocket may be formed by suddenly enlarging the material of the strip, as at 10^a, in Figure 6. It will be obvious that when the edges of this strip of material are straightened by their engagement with the straight clip strips 11 and 12, the excess material provided will 15 form a bulge or pocket in the cover in which the spring clip may operate without unduly wearing the cover or being interfered with in its operation by this cover.

Since the structure is capable of a certain 20 range of change and modification without materially departing from the spirit of my invention, I do not limit myself to the specific structure hereinbefore set forth except as hereinafter claimed.

25 I claim:—

1. A spring cover for the leaf springs of

vehicles comprising a tapered strip of material having at its longitudinal edges metallic strips attached thereto and having their free edge portions oppositely reverted to 30 provide interengaging hooks whereby the strip of material may be held in position about the spring and means for sealing the ends of the cover to the spring, each of said hooked portions of said strips having in its 35 bight a compressible element forming a packing.

2. A cover for the leaf springs of vehicles comprising a tapered strip of material and two clip strips, each clip strip having one 40 edge thereof reverted and clamped upon a corresponding edge of the strip of material, the free edges of the clip strips being oppositely reverted to provide interengaging hooks whereby the cover may be held in assembled relation about the spring and means for sealing the ends of the cover to the 45 spring.

In testimony whereof I hereunto affix my signature.

JOSEPH C. ANDEREGG.
